UNITED STATES PATENT OFFICE.

LOLA O. STASSART, OF PORTLAND, OREGON, ASSIGNOR OF TWO-THIRDS
TO O. W. MIELKE, OF PORTLAND, OREGON.

ENVELOP-SEALER.

No. 810,093.

Specification of Letters Patent.

Patented Jan. 16, 1906.

Application filed July 18, 1905. Serial No. 270,242.

To all whom it may concern:

Be it known that I, LOLA O. STASSART, a citizen of the United States, residing at Portland, in the county of Multnomah and State of Oregon, have invented a new and useful Envelop-Sealer, of which the following is a specification.

My invention relates to certain new and useful improvements in envelop-sealers, and has for its object to provide a very simple and cheap sealer and one that is very easily operated.

A further object of the invention is to provide a sealer with a moistening-pad attached to a tank, so that the pad will always be kept moist.

With these objects in view my invention consists of the novel features of construction, combination, and arrangement of parts hereinafter fully described, and pointed out in the claims.

In the drawings forming a part of this specification, Figure 1 is a perspective view of the sealer. Fig. 2 is a perspective view showing the moistening-pad and roller. Fig. 3 is a longitudinal section through the sealer. Fig. 4 is a section taken on line 4-4 of Fig. 3.

Referring to the drawings, A indicates the cylindrical tank, formed of a strip of metal bent back upon itself and soldered, having flange ends A' soldered thereon and having the end A² extending out forwardly, which is of greater width than the tank and is bent downwardly at A³, forming a side A⁴, the rear end being of a greater width than the front end, so that when the envelop having been moistened is drawn through from the rear it will be securely pressed together and stuck, and then inwardly under the end A² and having a curved edge A⁵, so that the envelop will pass through easily.

The tank A is provided with a screw-threaded neck A⁶, extending outwardly from the rear, in which the screw-threaded plug B', carried by the handle B, is adapted to be secured. The neck forms an opening through which the tank is adapted to be filled.

Secured to one of the ends A' by a screw C' is a wire frame C, on which is secured a metal strip C² by bending the side C³ around the bars of the frame, forming a support for the

felt pad D, one end of which extends upon the opening A⁷, formed at one end of the tank. The sides C⁴ of the strip C² are bent downwardly, forming ears, in which is journaled a roller C⁵, on which the sealer rolls. 55

The operation of the device is as follows: The operator takes hold of the handle of the sealer with his right hand and with his left hand shoves the envelop or other object to be sealed into the rear of the sealer, the flap of the envelop being drawn over the moistener and pressed together by the ends and securely sealed.

Having thus fully described my invention, 65 what I claim as new, and desire to secure by Letters Patent, is—

1. The combination with a tank, of a moistening-pad connected to said tank, and spaced plates carried by said tank for sealing 70 the article the under plate having a curved edge for the purpose described.

2. The combination with a tank of a frame detachably connected thereto, a pad carried by said frame, a roller carried by said frame 75 under the pad, and plates extending from said tank adapted to engage the envelop and flap, for the purpose described.

3. The combination with a tank provided with a spaced metal plate extending therefrom, of a frame detachably secured to said tank to the rear of the plates, and a moistener carried by the frame, a roller journaled in said frame supporting the tank and plate for the purpose described. 85

4. The combination with a tank provided with spaced metal plate extending therefrom, an opening formed in said tank, a handle secured in said opening and a moistener carried by the tank, for the purpose described. 90

5. The combination with a tank provided with spaced metal plate extending therefrom, an opening formed in the under side of the tank a frame detachably secured to said tank, a pad carried by said frame, and extending 95 up in the opening in the tank, a roller mounted on the frame and supporting the tank, and a removable handle connected to said tank, for the purpose described.

6. The combination with a tank provided 100 with a screw-threaded neck, and having spaced plates extending therefrom, the under

plate being cut away, an opening formed in the bottom of said tank, to one side, of a wire frame secured to one side of the tank, and projecting under the tank, a metal strip secured to said frame having downwardly-projecting ears, a pad secured on said strip, a roller journaled in said ears, and a handle se-

cured in said screw-threaded neck of the tank, for the purpose described.

LOLA O. STASSART.
